ROTARY PRESS

Ira C. Maxwell and Ole H. Langen, Minneapolis,
Minn., assignors, by mesne assignments, to The
Unipress Company, Incorporated, Minneapolis,
Minn., a corporation of Minnesota

Application April 26, 1948, Serial No. 23,204

18 Claims. (Cl. 38—5)

1

This invention relates to rotary presses employing a plurality of individual pressing machines. In carrying out the pressing operation using the usual air or power driven laundry machinery, it is necessary for the operator to lay the damp garment on the buck, then actuate the press to bring the presser head upon the buck, then permit the presser head to remain on the buck for at least a minimum period during which the garment is ironed dry and then open the press and remove the pressed garment therefrom. An appreciable length of time is required during which the press remains closed, and in order to obviate the labor cost of permitting the operator to stand without anything to occupy her attention during the ironing period, it has been customary to provide a plurality of presses in closely grouped or battery arrangement so that the operator may attend to opening a press, laying a fresh garment on the press and reclosing the press while another press in the battery is closed during the ironing portion of the cycle. In this mode of installation and operation, the presses are stationary and the operator must performe move from one press to another, which is inconvenient because the operator is required to move from press to press and therefore consumes energy in these useless and unproductive movements and is furthermore not provided with opportunity to rest by sitting on a stool while the work is done. Other disadvantages of the grouped press installations is that the timing of the cycle is dependent entirely upon the operator, although in some instances timers have been used for opening the press after a predetermined time has expired during the ironing cycle.

It is an object of the present invention to provide an improved pressing machine utilizing a battery of presses which are operated cooperatively, one after the other in sequential operation. It is a further object of the invention to provide an improved press battery wherein the individual presses are mounted for rotation, one after the other in front of an operator station and thence through a closed path of motion along which there is a closing station where the press is closed, and thence through a continuous further motion during which the press remains closed and the ironing operation is completed, and thence to an opening station at which the press is opened and thence return to the operator station where the operator removes the ironed garment and makes a fresh lay of an unironed garment on the buck for the next com-

2

plete cycle of operation. It is a further object of the invention to provide an improved battery of pressing machines in which the timing cycle is predetermined by the machine operation and in which a plurality of presses are utilized in order that the operator may be continuously engaged in removing the garment and making a fresh lay of one press after another, while the remaining presses of the battery are automatically undergoing the closing, ironing and opening functions of the cycle.

It is another object of the invention to provide an improved rotary press, including operator controlled means for regulating the speed of operation of the device. It is also an object of the invention to provide an improved rotary press having operator controls for starting and stopping the operation of the press and, optionally, including operator controls for providing continuous or intermittent (pausing) operation under the control of the operator, and if operated on the intermittent cycle, to provide rotation of the press until each press is successfully brought to the operator station at which the press is stopped and the rotation then restarted by the operator at the completion of the lay. It is also an object of the invention to provide improved rotary press wherein the closing, pressing and opening portions of the cycle are automatically controlled in timed sequence.

Other and further objects of the invention are those inherent in the apparatus herein illustrated, described and claimed.

The invention is illustrated in the drawings in which

Figure 1 is a plan view of the apparatus of the invention;

Figure 2 is a sectional view taken along the lines 2—2 of Figure 1, it being understood that in Figure 2 the rotation of the assembly is such as to show the open press at the point of closing and to show the closed press at the point of opening;

Figure 3 is a schematic view of the controls of one press of the pressing machine;

Figure 4 is a sectional view taken along the lines 4—4 of Figure 1;

Figure 5 is a wiring diagram of the motor device for rotating the press;

Figure 6 is a fragmentary view of the apparatus shown in Figure 1 showing a modified form of press control location;

Figures 7 and 8 are sectional views taken along the line 7—8 of Figure 6 and show the modified control at the press closing station

(Figure 7) and the press opening station (Figure 8);

Figure 9 is a modified form of press rotating arrangement wherein the motor and drive are completely housed.

Throughout the drawings corresponding numerals refer to corresponding elements.

Referring to the drawings the pressing machine includes a central floor plate 10 which is adapted to be placed or bolted upon the floor 11 on which the pressing machine is installed. Upon the plate 10 there is a central stationary pivot 12 which extends up and terminates near the top of the housing 14. The pivot shaft 12 serves to support suitable ball or sleeve bearings 15 which are mounted in the main flange 16 of the circular rotary frame plate 17. The flange 16 is also supported by a thrust bearing 18 which is mounted upon the plate 10 so as to receive the weight load at the center of the plate 17. The plate 17 is preferably of circular shape and near its periphery is reinforced by ring channels 20 and 21 which are positioned so that their flanges are oppositely directed and are of such a diameter as to leave a space between the webs of the flanges. Within this space are mounted a plurality of wheels 22 around the periphery of the ring channels 20 and 21. Greatest rigidity is provided by placing two or more of the wheels 22 under each of the presses that are mounted upon the rotary frame plate 17 so as to steady the plate 17 against vibration due to the opening and closing of the press. Plate 17 may, if desired, have radial stiffening webs not illustrated in order to increase its rigidity. The wheels 22 may be rubber tired, if desired, and the wheels 22 may run directly upon the floor 11 where the floor has sufficient evenness. Where the installation is made on a rough or uneven floor 11, it is preferable to place a circular sheet metal track 24 on the floor along the path where the wheels 22 track. The axis of each of the wheels 22 is radial in respect to the central pivot 12.

For rotating the circular frame plate 17 and all elements attached thereto, there is provided a belt 25 which may be a chain belt, as shown in Figure 1, which passes over a pulley 26 that is mounted upon radial arm 27, the arm being pivoted at 28 to the floor. An adjustment screw 30 mounted in the stationary bracket 31 is positioned so as to bear against the arm 27 so as to move it arcuately and thus permit tightening or loosening of the belt 25. The belt 25 also runs over the driven pulley 32. The pulley 32 rotates at slow speed and is preferably driven by an electric motor 34 through a gear box. We prefer to use a motor 34 which is capable of speed variations, such as a wound rotor repulsion induction motor, a shunt type direct current motor or the like. It is perfectly feasible to utilize an air driven motor 34 for constant or variable speed application where such is desired, the controls therefor being then appropriately selected for controlling the speed and operation of the motor 34.

Upon the rotary base 17 there are mounted a plurality of pressing machines generally designated A, B, C and D in Figure 1. Any suitable number of pressing machines greater than one may be utilized, depending upon the capacity of the unit and the type of work desired to be done by means of the installation. Four pressing machines of preferably identical character are shown in the illustrated embodiment of the invention and are spaced evenly around the rotary frame plate 17. The rotation of the frame plate

17 is in the direction of the arrow 35 and rotation of the drive pulley 32 is shown by the arrow 36. An operator station indicated by the floor pad 37 extends through approximately one-quarter of the circular path of motion of the floor plate 17 and presses A-D mounted thereon. Adjacent the terminating edge 38 of the operator station, there is provided a protective guard 40 which likewise extends through approximately one-quarter of the path of rotation of the floor plate 17 and the presses mounted thereon. The guard 40 roughly defines the closing station, it being understood that the guard extends somewhat ahead of and behind the position to which the presses close at the closing station so as adequately to safeguard any person from introducing members of their body on the press while the press is closed. From the termination of the closing station, which is at the position approximately shown by press B in Figure 1, and continuing in the direction of arrow 35, there is a portion of the path of motion during which the pressing part of the cycle takes place. During this portion of the cycle the pressing head is closed down upon the buck. The opening station is between the position in which press D is shown in Figure 1, which is still closed, and the leading edge 41 of the operator station. The closing station actuator is shown generally at 42 and the opening station actuator is shown generally at 45.

Adjacent the leading edge of the guard 40 there is a control panel generally designated 46, hereafter to be described in greater detail.

The presses A-D or any number which are mounted upon the rotary floor plate 17 may be of any desired individually powered driven presses. Present day presses are usually air driven and in the embodiment of the invention herein illustrated, the presses A-D are of the type shown in Patent Re. 22,041, although it is to be understood that any suitable air or other power driven press may be utilized. Thus, for example, the presses A-D can be single cylinder air driven presses of which the type shown in Patent 2,265,449 is exemplary.

To the top of the central standard 14 there is attached a rotary gland generally designated 47 which is connected to three concentric feed pipes 48, 49 and 50, two of which supply air under pressure and steam and the third serves as the condensate return of the presses. From the rotary gland 47 individual connections 48A-D, 49A-D and 50A-D are carried to the separate presses A, B, C, and D as shown for connections 50A-D in Figure 1. The gland 47 is of any suitable design and, in this instance, is supplied by the overhead feed and return pipes 48, 49 and 50. If desired, the central shaft 12 may be made hollow and of sufficient diameter so that the feed pipes 48, 49 and 50 may be introduced from the bottom rather than at the top as illustrated.

In the exemplified showing of the invention illustrated in Figure 2, each of the pressing machines includes a frame 52 which is suitably attached to the circular revolving frame plate 17.

The type of presses illustrated is a two-cylinder press, but as hereinbefore stated, this is merely exemplary of any type of power actuated presses that may be used. In the presses shown, each has a press frame and upon the frame 52 there is mounted a stationary buck 54 and a presser arm 55 which is pivoted at 56. The presser arm carries a presser head 57 which is movable from an open position (as shown for press A at the left in Figure 2), to the closed position (as shown for press D at the right in Figure 2). The move-

ment of the press from open to closed position and from closed to open position is accomplished by means of an air or other fluid motor consisting of a closing cylinder 58 and appropriate controls. Cylinder 58 is pivoted to the frame at 59 and to the rearwardly extending portion of the presser arm 55 at 60. In the illustrated presses the cylinders 58 are of low power but are sufficient to move the presser arms 55 from the full open position to a position close to the buck. The powerful squeezing requisite for ironing is accomplished by means of larger cylinders 61 which are pivoted to the frames at 62 and are pivoted at 64 to links 65, the upper end of link 65 in each press being pivoted at 66 to the rear portion of the presser arm 55. The pivot 64 is provided with a roller, not illustrated, which moves in a cam track 67 such that when the press is at nearly closed position the pivot 64 is permitted then to move in the rising cam slot 68 and thus apply a powerful jacking action on the rearwardly extending portion of the presser arm 55 so as thereby to apply heavy pressing force through the head 57 upon the buck 54. The control of air or other motor fluid to the cylinder 58—59 of each press is by means of a master operating valve generally designated 70 which is arranged to be moved between each of its two operating positions by pilot cylinders 71 and 72. In Patent Re. 22,041, which explains the operation of presses of this type, the corresponding closing cylinder and pilot cylinder are energized through two-hand control valves that are located near the front of the pressing machine on the work table beneath the bucks. In the present instance these two valves are, for example, located at 75 and 76 near the base of the press and when they are operated air under pressure is introduced from the gland 47 via pipe 18. Valves 75 and 76 are normally closed but when both are open, air is transmitted therethrough and thence through the pipe 79 to the press closing pilot cylinder 72. When pilot cylinder 72 is operated it moves the valve 70 in a direction such that air is admitted from line 80 through the valve 70 and thence through line 81 to both the closing cylinder 58 and also to the squeezing cylinder 61 which applies ironing pressure. In Patent Re. 22,041, the two-hand control valves admit air directly to the closing cylinder and the corresponding pilot valve controls air flow to only the squeezing cylinder. The results are, however, substantially the same and either air circuit may be used in presses of this character. Opening of the press is occasioned by the operation of a release valve 82 which in Patent Re. 22,041, is likewise mounted on the work table 14. In the present instance the release valve 82 is mounted near the bottom of the press frame. Valve 82 is normally closed by spring action, but when actuated air is admitted through it from line 18, thence via line 83 to the valve 82 and thence when the valve is actuated to line 84 which extends to the pilot cylinder 71 of the valve 70. This causes actuation of the valve 70 to the press opening position in which case the air in cylinder 61 is released through the valve 70 to the exhaust muffler 85. The foregoing controls are described in greater detail in Patent Re. 22,041. It is to be understood that any suitable controls for the presses A, B, C and D may be utilized and the specific illustration herein given is therefore only exemplary.

Each of the presses B, C and D is provided with a corresponding set of closing valves corresponding to 75 and 76 and with an opening or release 75 may be obtained.

valve corresponding to valve 82 of press A. These may be located at any location on the press or on the rotary frame 17 which is convenient. For example, they may be located at the front lower left portion of each press as illustrated in the present exemplified form of the invention or at any place on the rotating frame 17 or parts movable therewith so that the valves may be operated by stationary stops or cams as the presses move along. Thus, valves 75, 76 and 82 may be located on the frame 17 so as to be within the confines of the circular ring channel 24 so as to be operated by cams thereunder, as shown in Figures 6, 7 and 8.

In Figures 6, 7 and 8 there is shown a modified installation of the control valves in which only one valve 76A is used for controlling the air flow to the press closing pilot cylinder 72 and hence closure of the press and another valve 82A is used to control the flow of air to the press opening pilot cylinder 71 and hence opening of the press. Both valves are mounted on a plate 73 and form an assembly which is mounted, one assembly for each press, in a convenient location on plate 17, as for example at AA, for press A, BB for press B, CC for press C and DD for press D, Figure 1. It is understood, of course, that the control assemblies may be at any convenient location. In Figures 5, 6 and 7 the control cam 86A (Figure 7) for operating the valves 76A (and the corresponding valves for the remaining presses) is mounted on the floor 11 at a position such that the valve 76A etc. would be operated when the corresponding press reaches the closing position within the confines of guard 49. Thus, the cam would be under plate 17 and at position BB of Figure 1 or slightly in advance or behind such position. The criterion is to have the press close after the press has reached a safe location within the space provided and guarded by the guard 40 and panel board 38. The closing cams are located accordingly. It is noted that two valves corresponding to 75 and 76 of Figure 3 are not used in this modified form since the cams and valve stems are enclosed by the press turn-table 17, and hence accidental operation is unlikely. However, two valves may be used if desired for extra safety. The cam 90A (Figure 8) for operating the press open pilot cylinder for opening the press is located so that at the opening position the valve 82A for press A and the corresponding valves of the other presses are actuated and the presses opened as each press comes around to the opening position of Figure 1. Thus, cam 90A is at approximately the position DD of Figure 1 so that each press is opened as it reaches approximately the position of press D in Figure 1 or, if desired, even nearer the leading edge 41 of operator station 37. The criterion is to have each press open as it comes to the operating station and the opening cam is located accordingly.

The valves 75 and 76 in the illustrated embodiment are positioned so that their operating stems are located to be engaged by a pair of operating cams 86 and 87 that are mounted on pedestal 88 in the housing 42 shown in Figure 1. When the rotary frame 17 moves each press past the closing station 42, Figure 1, the cams 86 and 87 engage the stems of the valves 75 and 76 of each press and thereby cause actuation of the then open press to closed position. It may be pointed out that two valves 75 and 76 are utilized in order that greater safety for the device may be obtained. This prevents accidental

operation of the press in the event an operator or stranger should accidentally kick one of the valves 75 or 76.

Thus, as each press reaches the closing station 42 the cams 86 and 87 cause simultaneous actuation of the press and the presser head 57 closes upon buck 54. The continued rotation of the frame 17 carries the then closed press in the direction of arrow 35 and the pressing action takes place until the operating controls of the press are brought adjacent the opening station 45 at which place a single cam 90, which is mounted upon a pedestal under the cover 45, actuates the operating stem of the release valve 82, thereby causing release of each press as it comes past the opening station 45. The then open press continues around through the operator station 37. The operator removes the pressed garment and lays a fresh unpressed or damp garment on the buck while the rotation is continued, or two operators, if desired, may be at the operating station 37, one who will remove the garments and another to place the unpressed garments on the buck. The then open press with the unpressed garment on the buck then continues around to the station 42 where closure of the press is occasioned as previously described.

Referring particularly to Figures 1, 4 and 5, at 46, Figure 1, there is provided a vertical panel board which is shown in elevation in Figure 4. Upon the panel board there are mounted the operator controls by which a variety of operations of the machine may be achieved. In the operation previously described the drive motor 34 rotated continuously and thus continuously moved the presses about their circular path of travel. In order to vary the speed of operation of the motor 34 so as to suit the needs of the work being done and the skill of the operator, there is provided a speed control 92 which includes a rotating knob and suitable control operated thereby and mounted within the confines of the panel board 46. The particular speed control which is used depends upon the type of motor drive 34. Thus, in the exemplary embodiment of the invention an adjustable speed direct current motor or repulsion induction motor 34 may be used, in which case the control operated by the speed control handle 92 is a variable resistor 93 of suitable design. Such a motor and control are illustrated in the wiring diagram, Figure 5. For other types of electric, hydraulic or air motor drives the control element 93, which is operated by the speed control knob 92, is selected according to the type of motor and power source utilized. In this manner the speed of rotation of the supporting platform 17 and the presses carried thereby may be adjusted to suit the work and skill of the operator.

In order to stop and start rotation there are provided start and stop buttons 94 and 95, respectively, which are connected to the motor element 34 so as to start and stop its operation. Thus, as illustrated in the wiring diagram these constitute a push button switch 96 having the start button 94 and the stop button 95. By pushing the start button the circuit to the motor 34 is completed and, other conditions being satisfied, the motor 34 starts and rotates the press-carrying platform. In order to stop rotation the stop button 95 is pressed, thus opening the circuit in discontinuous operation.

In some instances it is desirable to have an

intermittent rather than continuous operation in order that the operator may not be caused to do unacceptable work because of unavoidable or occasional delay in removing the pressed garment or making the lay of the unpressed garment or other causes. To provide for selective control of continuous or intermittent operation, there is provided a stopping control 97 which is mounted, for example, near the base of control panel 46 and closely adjacent the periphery of the rotary supporting platform 17. The stopping control in the present instance is illustrated by the power switch 97 which has an operating stem 98 positioned so as to be in the path of movement of cams 98A, 98B, 98C and 98D which are mounted on any part of the rotary platform 17 or on any apparatus carried thereby. As herein illustrated cams 98A-98D are mounted on platform 17 which is a convenient location. As shown in the circuit diagram, Figure 5, which is exemplary of the type of control used, the switch 97 is normally closed and is moved to the open position successively by the cams 98A through 98D. As each press reaches the position shown for press A in Figure 1, its corresponding stopping cam 98A through 98D is in position to press the operating stem of the switch 97, and this interrupts the power circuit of the motor 34 and thereby causes the motor to stop. In order to restart the rotation of the platform 17 there is provided a normally open operator push button 100 which is connected in parallel to the stopping switch 97. Thus, even though one of the cams 98A through 98D has pressed against the stem 98 and opened switch 97 thereby stopping the motor 34, rotation can be restarted by the operator by pushing on restart switch 100 which serves to close the contact around switch 97. By making the peak of cams 98A through 98D relatively sharp, only a momentary pressure on button 100 is required for as soon as rotation has begun the cam, which has then been pushing upon the stem 98 of the stopping switch 97, moves out of alignment with the switch, and operation may then continue through the then closed switch 97, thus permitting the restart switch 100 to be released. When utilizing intermittent operation, each press comes around to the position shown for press A in Figure 1 and then stops. The operator may, if she has before the stop occurs already removed the pressed garment and has laid the unpressed garment on the buck, simply hold the button 100 down, even before rotation of the platform 17 stops, and in such case rotation simply continues by virtue of the continuous circuit which is maintained through the restart 100, regardless of the momentary opening of switch 97. However, if the operator is delayed and does not have the time to complete the lay of the garment and place an unpressed garment on the buck, the rotation stops and is not resumed until the operator pushes restart switch 100.

In order to provide optional control for either the foregoing interrupted (pausing) operation or continuous operation, there is included a two-button control switch 101 having a "continuous" operation push button 102 for continuous rotation operation and "intermittent" operation push button 103 for the interrupted or pausing type of operation. The switch 101 is connected, as shown in Figure 5, so as to bridge contacts 97. When it is desired to have continuous operation the button 102 is pushed, thus permanently clos-

ing switch 101. Rotation of the platform 17 is therefore continuous as described above, regardless of the opening of switch 97 which may be occasioned by the rotation. When an interrupted or pausing type of operation is desired, as also described above, the button 103 is actuated, thus moving switch 101 to the open position. In this instance, when switch 97 is opened automatically by the cams 98A through 98D, the rotation is stopped until restarted by the momentary closure of switch 100 or unless switch 100 is held closed while 97 opens. It may be pointed out that the switch 101 remains in either of its two operating positions.

If desired, the location of cams 98A through 98D on the rotating platform 17 may be such that the halting position is more closely adjacent the trailing edge 38 of the operator station 37 rather than centrally thereof, as shown in Figure 1. This is accomplished by moving each of the cams 98A to 98D to positions more closely adjacent the presses to which they respectively correspond.

A slightly modified form of motor drive for rotating the press carrying frame is shown in Figure 9. In this figure a chain sprocket or other suitable drive gear 110 is bolted or riveted to the flange of member 16 which serves to mount turn-table frame member 17. A link chain connects gear 110 and drive gear 111 on the geared motor assembly 112, the latter being of squat design so that it is wholly enclosed beneath turn-table 17.

As many apparently widely different embodiments of this invention may be made without departing from the spirit and scope thereof, it is to be understood that we do not limit ourselves to the specific embodiments herein.

What we claim is:

1. A pressing machine comprising a frame, means mounting the frame for rotary motion around a vertical axis of rotation, a plurality of pressing machines mounted at spaced intervals around said frame for movement therewith around a closed path having a closing station, an opening station and an operator station, each pressing machine having a buck and a presser head movable into and out of cooperating engagement with the buck, motor means and a closing control and an opening control therefor on each press for causing said cooperative movements of the presser head, frame rotating motor means connected to the frame for rotating the frame, a closing control actuating protuberance at said closing station and positioned so as to actuate an extending cam follower to actuate the closing control of each press thereby to close said press as the frame moves the press past the closing station, and an opening control actuating protuberance located at said opening station and positioned to actuate said opening control of each press thereby to open it as each press is moved past said opening station, said apparatus being further characterized in that a guard is provided around the path of movement of the presses throughout at least that portion of said movement during which the press closes.

2. A pressing machine comprising a frame, means mounting the frame for rotary motion around a vertical axis of rotation, a plurality of pressing machines mounted at spaced intervals around said frame for movement therewith around a closed path having a closing station, an opening station and an operator station, each pressing machine having a buck and a presser head movable into and out of cooperating en-

gagement with the buck, motor means and a closing control and an opening control therefor on each press for causing said cooperative movements of the presser head, frame rotating motor means connected to the frame for rotating the frame, a closing control actuating means at said closing station and positioned so as to actuate the closing control of each press thereby to close said press as the frame moves the press past the closing station, and an opening control actuating means located at said opening station and positioned to actuate said opening control of each press thereby to open it as each press is moved past said opening station, said closing control of each press comprising separated pneumatic elements mounted for independent actuation, each being connected to the motor means of its press in a manner such that simultaneous actuation of said separated elements is required to actuate said motor means and operate the press, said pneumatic elements each having an extending cam follower, said closing control actuating means being provided with stationary portions externally positioned with respect to said frame for simultaneously engaging said extending cam followers and actuating said separated elements simultaneously at said closing station.

3. The apparatus of claim 2 further characterized in that means is provided for varying the speed of rotation of said frame rotating motor means whereby the speed of rotation of said frame may be varied.

4. The apparatus of claim 2 further characterized in that said frame rotating motor means has a speed controller connected thereto, said speed controller being located convenient to said operator station.

5. A rotary multiple unit pressing machine comprising frame means mounted for rotation around a vertical axis of rotation, a plurality of pressing machines mounted at evenly spaced intervals on said frame so as to be rotatable therewith, an operator station, press closing station and press opening station at spaced intervals around the path of motion of the pressing machines, each pressing machine having a buck, a head, motor actuating means for causing the head to move into closed position in cooperative pressing engagement with the buck and into open position away from the buck, a closing control comprising a pair of independently operable members which must be actuated simultaneously to cause closure of the press and an opening control comprising an independently operable member, stationary closing cam means at the closing station positioned to actuate the pair of independently operable members of the closing control of each press and thereby close each press as it reaches the closing station and stationary opener cam means at the opening station positioned to actuate the opening control of each press and thereby open the press as it reaches the opening station, and frame rotation motor means connected to the frame for rotating it and the presses thereon.

6. In a pressing machine having a frame mounted for rotation about an upright axis on a supporting surface, said frame having a plurality of pressing bucks spaced therearound and a circular rim positioned adjacent the supporting surface, a presser head mounted for cooperative movement into and out of engagement with each buck and having a steam chamber and an air motor press operating means and controls therefor for effecting said movements as the frame is

rotated, motor means positioned outside the path of movement of the frame and including a drive means on an upright axis and a belt around said means and circular rim drivingly connecting them for rotating the frame, a source of air under pressure connected to said air motor means, a source of steam under pressure connected to said steam chambers and a steam condensate return connected to said steam chambers and said connections of air, steam and condensate return being made to each press through a gland concentric about the axis of rotation of the press frame.

7. The apparatus of claim 6 further characterized in that the connections of air, steam and steam condensate return are through overhead pipes to said concentric gland.

8. A pressing machine comprising a frame, means mounting the frame for rotary motion around a vertical axis of rotation, a plurality of pressing machines, each having a buck, a presser head and an air motor connected to the head for moving it into pressing engagement with the buck, said pressing machines being mounted at spaced intervals on and around said frame for rotary movement therewith around a closed path having said vertical axis as the center, each of said presses including a valve which is movable to a press-closing position for introducing air into the air motor of said press for closing said press and which is movable to a press-opening position for exhausting the air from said air motor for opening the press, a closing cam follower, and means connecting the cam follower to said valve for moving said valve to press closing condition, and an opening cam follower and means connecting the opening cam follower to said valve for moving said valve to press opening position, said closed path of motion of the frame and presses thereon being divided into portions for the closing, pressing, opening and loading operation of said presses as they move through said portions of said closed path, stationary closing cam means located so as to be briefly engaged by the closing cam followers of said presses for moving said cam followers and the press valves actuated thereby to press closing position successively as the presses move through said closing portion of said path, and stationary opening cam means located so as to be briefly engaged by the opening cam followers of said presses and out of the path of movement of said closing cam followers for operating said opening cam followers and the press valve operated thereby to press opening position successively as the presses move said opening portion of said path.

9. The apparatus of claim 8 further characterized in that said cam followers are vertically reciprocating mechanical elements.

10. The apparatus of claim 8 further characterized in that said closing and opening cam followers pneumatically actuate said press control valve.

11. The apparatus of claim 8 further characterized in that said cam followers are located on said frame and rotatable therewith and said stationary cam opening means are placed externally of said frame and are adapted to be engaged once during the rotation of said frame by the opening cam followers for each of said machines.

12. The apparatus of claim 11 further characterized in that the closing cam follower of each press comprises a plurality of reciprocating elements adapted to connect an air supply source to said air motor, and said reciprocating elements acting in unison therefor.

13. The apparatus of claim 11 further characterized in that a guard is provided around the path of movement of the presses throughout that portion of said movement during which the press closes.

14. A pressing apparatus comprising a frame, means mounting the frame for rotary motion about a vertical axis of rotation, a plurality of pressing machines each having a buck, a presser head and an air motor connected to the head for moving it into pressing engagement with the buck, said pressing machines being mounted at spaced intervals on and around said frame for rotary movement therewith around a closed path having said vertical axis as the center, each of said presses including a valve which is movable to a press closing position for introducing air into the air motor of said press for closing said press and movable to a press opening position for exhausting the air from said air motor for opening the press, a closing cam follower pneumatically connected to said valve for moving said valve to press closing position, an opening cam follower pneumatically connected to said valve for moving said valve to press opening position, said closed path of motion of the frame and presses thereon being divided into portions for the closing, pressing, opening and loading operation of said presses as they move through said portions of said closed path, stationary closing cam means external to said frame and located so as to be engaged by the closing cam followers of said presses for directly mechanically moving said cam followers and the press valve actuated thereby to press closing position successively as the press is moved through said closing portion of said path and stationary opening cam means located so as to be engaged by the opening cam followers of said presses and out of the path of movement of said closing cam followers for directly mechanically operating said opening cam followers and the press valve operated thereby to press opening position successively as the press is moved through said opening portion of said path, and said stationary opening cam means being positioned on a station immediately preceding the opening position of said path of travel and said closing cam means being positioned at a station immediately preceding said closing path of travel.

15. The apparatus of claim 14 further characterized in that said closing cam means comprises a plurality of horizontally extending projections adapted to contact said closing cam followers throughout a relatively small segment of travel of said frame through said closed path and safety means protecting said stationary cam means.

16. The apparatus of claim 14 further characterized in that a vertically extending guard is provided positioned adjacent the periphery of said frame and extending throughout the closing portion of said path of travel.

17. In a pressing machine having a frame mounted for rotation about an upright axis, said frame having a plurality of pressing bucks spaced therearound, a presser head mounted for cooperative movement into and out of engagement with each buck, and press operating motor means and controls therefor for effecting said movements as the frame is rotated, motor means for rotating the frame, said press operating motor means being air motor means and said presser heads being chambered so as to be heated by steam, a source of air under pressure connected to said press operating motors, a source of steam under pres-

13

sure connected to said steam chambers and a steam condensate return connected to said steam chambers, said connections of air for operating the press operating means and said steam and steam condensate return each being made to each 5 press through a concentric gland located at the axis of rotation of the press frame.

18. The apparatus of claim 17 further characterized in that the connections of air, steam and steam condensate return are through overhead 10 pipes to said concentric gland.

IRA C. MAXWELL.
OLE H. LANGEN.
